CLAIM

What is claimed is an ornamental design for a barbecue grill with integrated beverage dispenser, as shown and described.

DESCRIPTION

FIG. 1 is a top, front, right perspective view of a barbecue grill with integrated beverage dispenser showing our new design;

FIG. 2 is a front plan view thereof;

FIG. 3 is a rear plan view thereof;

FIG. 4 is a left plan view thereof;

FIG. 5 is a right plan view thereof;

FIG. 6 is a top plan view thereof; and,

FIG. 7 is a bottom plan view thereof.

Wherein the broken lines show environmental structure that forms no part of the claimed design.

1 Claim, 5 Drawing Sheets
